FINGER TIP MOISTENER

Robert P. Ingraham, San Antonio, Tex.

Application December 27, 1946, Serial No. 718,698

1 Claim. (Cl. 15—227)

1

This invention relates to moistening devices, and more particularly to moisteners adapted to be supported for convenient use on a finger of the user.

An object of this invention is to provide an improved finger-supported device adapted to conveniently moisten the dry mucilage usually provided on stamps, envelopes, stickers, adhesive tape, or the like.

A further object of this invention is to provide an improved moistening device which is adapted to be supported on a finger or digital member of the user and which is capacitated to absorb a liberal quantity of moistening liquid from an external fountain or from a self-contained receptacle and conveniently apply the liquid to adhesive surfaces to moisten the same.

A specific object of this invention is to provide an improved laminated moistening device having an inner lamina shaped to substantially conform to and receive the outer portion of a finger of the user to thereby secure the device to the finger, a liquid-retaining member or lamina surrounding the inner lamina, and an outer lamina formed of porous or capilliform material surrounding the liquid-retaining lamina, the inner lamina being preferably formed of a material which is impervious to the moistening liquid.

A more specific object of this invention is to provide an improved laminated moistening device having an inner lamina shaped to receive the outer portion of a finger or digital member of the user to thereby detachably secure the device to the finger, a lamina of cellulated yieldable material surrounding the inner lamina; a lamina of soft, yieldable porous material surrounding the cellulated material, and means for applying water or other moistening liquid to the cellulated material.

It is also an object of this invention to provide a finger tip moistener of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in form, proportion and minor details of construction may be made within the scope of the claim without departing from the spirit or sacrificing any advantages of the invention.

For a complete disclosure of the invention, a

2

detailed description thereof will now be given in connection with the accompanying drawings, forming part of the specification, wherein:

Figure 1 is a perspective view of a form of the improved moistener;

Figure 2 is a longitudinal vertical sectional view taken through a supply fountain and depicting the moistener in side elevation and supported in the saddle of the fountain;

Figure 3 is a vertical transverse sectional view taken on the line 3—3 of Figure 2;

Figure 4 is a fragmentary longitudinal sectional view taken through a modified form of the invention;

Figure 5 is a perspective view of another modified form of the invention; and

Figure 6 is a transverse sectional view taken on the line 6—6 of Figure 5.

Referring to the drawings, in which similar reference characters designate corresponding parts, 10 and 10a indicate different forms of a soft yieldable laminated moistening device adapted to be supported on a finger or digital member of the user in convenient position to apply water or other suitable moistening liquid to adhesive surfaces of stamps, envelopes, stickers, adhesive tape or the like.

The moistener depicted in Figures 1, 2 and 3 includes an inner lamina or lining 11 formed of soft yieldable material which is impervious or resistant to water or other moistening liquids, and it is normally of cylindrical formation having an open outer terminal surrounded by an annular thickened portion or bead 12, and its inner terminal is closed by a semispherical end wall 13. A tubular lamina 15 of soft, yieldable, porous material, such as sponge rubber, conforms to and surrounds the cylindrical side wall and closed end wall 13 of the inner lamina 11, and it is preferably cemented or otherwise secured thereto. The thickest portion 16 of the lamina 15 surrounds the semispherical end wall 13 of inner lamina 11, then its thickness is gradually decreased as it approaches the open end of the lamina 11, and it terminates at or adjacent the annular bead 12, as indicated at 17.

An outer tubular lamina 18 of soft, yieldable, porous material, such as soft leather or chamois, is secured to and completely surrounds the lamina 15, and its open terminal is secured to the inner lamina 11 at or adjacent the annular bead 12, as indicated at 20. The upper or back portion of the outer lamina 18 is preferably painted with a thin layer of rubber or other water-resisting material 19.

A fountain, well, or receptacle 21 is provided,

and it includes a chamber 22 for holding a liberal quantity of water or other suitable moistening liquid, and the liquid is supplied to the chamber through a filling aperture 23 formed in its upper or top wall 25. The upper wall 25 has a concave and perforated or slotted saddle 26 depending therefrom into the water chamber 22. An arcuate lip or stop 27 extends upwardly from the top wall 25 and forms a continuation of the saddle 26, for a purpose to be hereinafter explained.

When not in use, the moistening device 19 rests in the saddle 26 of the fountain 21 with a portion of it immersed in the moistening liquid so that the lamina 15 absorbs a liberal quantity of the moistening liquid from the fountain. The axis of the moistening device is inclined so that a finger of the user may be conveniently passed through the open end of and into the tubular inner lamina 11. When the finger is inserted, the yieldable inner lamina 11 substantially conforms to the finger, and the elastic bead 12 grips the finger sufficiently to hold the moistener thereon. While the finger is being inserted into the moistener, the moistener is held against movement away from the finger by the rounded lower end of the saddle 26 and the stop lip 27.

When the moistener is secured to the finger, it is manipulated so that the lower portion of the porous outer lamina 18 engages and moves along the adhesive surface which is to be moistened. This liberates sufficient liquid from the liquid retaining lamina 15, through the porous lamina 18 and onto the surface to moisten the dry adhesive to adhesive state. After the desired moistening operations are completed, the moistener is returned to the open saddle 26 of the fountain 21, where it absorbs a replenishing supply of liquid preparatory to future use.

In the form of the invention depicted in Figure 4, a liquid-supply tank or receptacle 30 is provided which is communicated with the cellular liquid-absorbing lamina 15 through a perforated or foraminous bottom portion 31 and the outer porous lamina 18. A filling-neck 32 is provided for the tank and it is closed by a removable screw-cap or closure 33. The tank may be formed of metal, plastic, rubber or any suitable material, and its bottom is shaped to conform to the outer lamina 18, and it is cemented or otherwise secured thereto.

In this arrangement, the moistening liquid is supplied from the tank 30, and its supply of moistening liquid may be replenished when desired by simply removing the screw-cap and filling the tank through the neck or filling opening 32.

In the form of the invention depicted in Figures 5 and 6, the inner lamina 11a of the moistening device 10a is preferably formed of resilient material, such as thin metal or plastic, shaped to substantially conform to the lower outer portion of a finger of the user. The upper portion of the inner lamina 11a is open to permit the finger to be inserted into the moistening device, and its upper terminals are rolled outwardly to provide a circular chamber or tank 30a for the reception of water, or other moistening fluid. A liquid absorbing and retaining lamina 15a surrounds the inner lamina 11a, and a porous lamina 18a surrounds the absorbing lamina. The outer edges of the rolled portion 11a bind the upper or outer terminals of the lamina 15a and 18a to the in-

ner plastic lamina 11a, thus providing a watertight joint for the liquid-retaining tank 30a. A filling opening or neck 32a is provided for the tank 30a and this opening is normally closed by a screw-cap or closure 33a. The liquid-retaining tank 30a is preferably of U-shape formation, as best seen in Figure 5, in order to permit the outer portion of the finger to be inserted into the moistening device.

In use, the device may be supported on a finger of the user by merely forcing the finger past the rolled portions of the resilient inner lamina 11a into the stall defined by the lamina. Now the moistening device may be moved along a surface of dry adhesive until sufficient quantity of moistening liquid has been deposited thereon to moisten it to adhesive state. When the supply of moistening liquid is exhausted, it may be conveniently replenished by removing the screw cap 33a and pouring a sufficient quantity through the opening 32a.

This form of the invention may also be used with the fountain 21 to receive its supply of moistening liquid therefrom. In this event the filling-neck 32a and cap 33a may be omitted and the rolled portion of the inner lamina 11a may be made smaller.

Having thus described my invention, what I claim as new and useful is:

A finger-supported moistener including an inner lamina formed of flexible material which is impervious to the moistening liquid employed and shaped to substantially conform to and entirely enclose the outer portion of the finger of the user and having a finger entrance opening formed therein, said moistener capable of freely rotating upon the finger a relatively thick and substantially rigid finger-holding portion surrounding the finger entrance opening, a lamina of liquid-absorbing and retaining material entirely surrounding the inner lamina and adapted to absorb and retain a quantity of the moistening liquid, and an outer lamina formed of porous material entirely surrounding said liquid-absorbing lamina.

ROBERT P. INGRAHAM.
